Primary Examiner—Lucy Lieberman**[57]****CLAIM**

The ornamental design for a wall mounted strap for holding coiled cords, as shown and described.

DESCRIPTION

FIG. 1 is a perspective view of the wall mounted strap for holding coiled cords showing my new design, the strap being in a functional position;

FIG. 2 is a front elevational view of a wall mounted strap for holding coiled cords showing my new design;

FIG. 3 is a right side elevational view thereof;

FIG. 4 is a top plan view thereof; and,

FIG. 5 is a bottom plan view thereof.
